UNITED STATES PATENT OFFICE

CLYDE D. McCANN, OF DES MOINES, IOWA, ASSIGNOR TO CAPITAL CITY ELECTRIC COMPANY, OF DES MOINES, IOWA, A CORPORATION OF IOWA

DESIGN FOR A COMBINATION LIGHT FIXTURE AND MIRROR

Application filed May 2, 1932. Serial No. 43,689. Term of patent 7 years.

To all whom it may concern:

Be it known that I, CLYDE D. McCANN, a citizen of the United States, and a resident of Des Moines, in the county of Polk and State of Iowa, have invented a new, original, and ornamental Design for a Combination Light Fixture and Mirror, of which the following is a specification, reference being had to the accompanying drawing, forming part thereof.

The figure is a front view of my combination light fixture and mirror, showing my new design.

I claim:

The ornamental design for a combination light fixture and mirror, substantially as shown.

CLYDE D. McCANN.
